UNITED STATES PATENT OFFICE.

JULIUS GROSSMAN, OF NEW YORK, N. Y., ASSIGNOR TO EAGLE LITES, INC., A CORPORATION OF NEW YORK.

DESIGN FOR A LIGHTING-FIXTURE BACKPLATE OR ANALOGOUS ARTICLE.

Application filed September 21, 1928 Serial No. 28,228. Term of patent 3½ years.

To all whom it may concern:

Be it known that I, JULIUS GROSSMAN, a citizen of the United States, and a resident of 1055 Jerome Avenue, city of New York, county of Bronx, and State of New York, have invented a new, original, and ornamental Design for a Lighting-Fixture Backplate or Analogous Article, of which the following is a specification, reference being had to the accompanying drawing, forming a part thereof,

In the drawing:

Figure 1 is a front elevational view of the lighting fixture backplate or analogous article; and

Figure 2 is a diagrammatic edge view of the same.

I claim:

The ornamental design for a lighting fixture backplate or analogous article substantially as shown.

JULIUS GROSSMAN.
